ARROW POINT ADAPTERS

William E. Sweetland, Eugene, Oreg.

Application May 14, 1958, Serial No. 735,336

3 Claims. (Cl. 273—106.5)

The present invention relates to adapters for arrow points and particularly for adapters for mounting standard points to arrow shafts that are slightly smaller in diameter than standard.

Most arrow points are designed to fit standard arrow shafts, usually made up from natural wood, but shafts that are made from compressed wood, such as cedar, or from glass or aluminum are of a smaller diameter than are the natural wood shafts.

Due to the fact that expensive dies are required for the making of arrow heads, the arrow head manufacturers have been slow to change the structure of dies to fit the smaller shafts, therefore the primary object of this invention is to provide an adapter to be applied to these substandard diameter shafts so that the standard arrow head can be applied thereto.

A further object of this invention is to provide an adapter formed of relatively soft or resilient material so that it will absorb shock when striking an object, protecting the shaft from breakage.

The above object can be carried out by not only a soft material, such as aluminum, but by a more resilient material such as plastic, rubber or the like.

A further object of the invention is to provide an adapter of the class described above having ribs or grooves formed thereon to provide a cushioning action to absorb the shock in the protecting of the arrow point when the point strikes a hard object.

Another object of this invention is to provide an adapter which will extend the arrow length so that additional clearance will be allowed to the back of a hunting point, or other type of point.

Other objects and advantages will become apparent in the following specification when considered in the light of the attached drawings, in which:

Figure 1 is a side view of an adapter mounting an arrow point to a short section of arrow shaft, parts broken away for convenience of illustration.

Figure 2 is a sectional view, taken on the line 2—2 of Figure 1, looking in the direction of the arrows.

Figure 3 is a fragmentary side view of a modified form of the invention with parts broken away for convenience of illustration.

Figure 4 is a sectional view, taken on the line 4—4 of Figure 3, looking in the direction of the arrows.

Figure 5 is a fragmentary side view of another modified form of the invention with parts broken away for convenience of illustration.

Figure 6 is a sectional view, taken on the line 6—6 of Figure 5, looking in the direction of the arrows.

Figure 7 is an enlarged fragmentary side view of the adapter shown in Figure 5 illustrating the conditions at the moment of impact with parts broken away for convenience of illustration.

Figure 8 is a perspective view of the adapter disclosed in Figure 1.

Figure 9 is a side view of still another modified form of the invention with parts broken away for convenience of illustration.

Referring now to the drawings in detail wherein like reference numerals indicate like parts throughout the several figures, the reference character P indicates generally a conventional hunting arrow point. The point P includes a cone-shaped hollow body member 10 provided with two or more fins or blades 11 forming part thereof. The cone-shaped body 10 provides a cone-shaped socket 12 for receiving a cone-shaped end 13 of an arrow shaft 14.

Arrow shaft 14 made from a compressed wood, such as cedar, from glass or aluminum, has a diameter smaller than standard and an adapter bushing 15 is disposed between the socket 12 of the body 10 and the cone-shaped end 13 of the shaft 14.

The inner surface of the adapter 15 is glued, or otherwise fixedly secured to the end 13 of the shaft 12, and is also glued or otherwise fixedly secured to the inner walls of the socket 12 of the body member 10. The material from which the adapter 15 is made is preferably of a softer or more resilient material than the body 10 so that a striking shock on a hard object can be absorbed within the adapter bushing 15.

A modified form of the invention is shown in Figures 3 and 4 wherein an adapter 15a is provided with longitudinal flutes 16 for absorbing shock. The flutes 16 are glued to the socket 12 to secure the point P thereto.

Another modified adapter 15b is illustrated in Figures 5, 6 and 7, wherein annular ribs 17 are formed thereon with glue G applied to the end 13 of the shaft 14 to secure the same to the inner surface of the adapter 15b and also glue is applied to the outer surface 18 of the rib 17 to hold the same securely within the cone-shaped socket 12 of the arrow point P, referring particularly to Figure 7. Figure 7 also illustrates how the shock is absorbed by the bending of the annular ribs 17.

Referring to Figure 9, a further modification is illustrated wherein an adapter 20 is applied to the end 13 of the arrow shaft 14 and is formed to receive a point P'. A feature of this form of the invention is to lengthen the arrow shaft 14 and also to absorb shock on striking a target.

Having thus described the preferred embodiments of the invention, it should be understood that numerous structural modifications and adaptations may be resorted to without departing from the scope of the appended claims.

What is claimed is:

1. In an arrow of the type including an arrow point having a conical socket and an arrow shaft having a conical end normally received in said socket, a shock absorbing adapter bushing comprising a resilient hollow conical body having the opposite ends thereof open, said body having a wall of generally uniform thickness with the hollow body forming an internal conical socket, and a plurality of resilient ribs integrally formed on the outer surface of said body, said adapter engaging over and fixed to the conical end of said shaft with the conical socket of said arrow point engaging over said adapter supported on and fixed to said ribs.

2. A device as claimed in claim 1 wherein said ribs extend longitudinally of said adapter.

3. A device as claimed in claim 1 wherein said ribs are annular and are formed on said adapter in spaced apart parallel relation.
